UNITED STATES PATENT OFFICE.

PHILIP HERDER, JR., OF CLEVELAND, OHIO.

STEP-LADDER.

SPECIFICATION forming part of Letters Patent No. 757,616, dated April 19, 1904.

Application filed September 9, 1903. Serial No. 172,533. (No model.)

To all whom it may concern:

Be it known that I, PHILIP HERDER, Jr., a citizen of the United States, residing at Cleveland, in county of Cuyahoga and State of Ohio, have invented certain new and useful Improvements in Step-Ladders; and I do hereby declare the following to be a full, clear, and exact description of the invention, such as will enable others skilled in the art to which it applies to make and use the same, reference being had to the accompanying drawings, and to the marks of reference thereon, which form a part of this specification.

My invention relates to certain new and useful improvements in step-ladders; and it consists in the construction and combination of the parts, as will be hereinafter set forth and specifically claimed.

The object of this invention is to provide a step-ladder in which the step-section and prop-section are so connected that the parts may be positioned to provide an extension-ladder, such result being accomplished by connecting the parts so that the prop-section may be slid through connecting-fixtures when the sections are parallel, thereby permitting the relative position of the parts to be changed without completely inverting one of the sections, the construction also permitting the prop-section to be adjusted as desired.

In the accompanying drawings, Figure 1 is a perspective view showing the parts positioned for use as an ordinary step-ladder. Fig. 2 is a side elevation showing the parts arranged as an extension-ladder. Fig. 3 is a detail perspective view of a bracket-plate, the guide pivoted thereto, and the stop-pin of the prop-section. Fig. 4 is a sectional view, and Figs. 5 and 6 detail views.

A refers to the main or step section of the ladder and comprises side pieces a , steps A' , and a platform A'' , all of ordinary construction. The corners of the platform are cut away, as shown at a' , and between the platform and the first step there is pivoted a shelf E' . To the under side of the platform, between the side pieces, are pivoted plates B'' , the point of connection and the size of the plates being such that when the plates are turned on their pivots the ends, which are

shaped to form hooks, will be positioned beyond the edge of the platform.

The brackets C are rigidly attached to the side pieces of the step-section of the ladder between the platform and the upper step, and to the projecting ends of the brackets C are pivoted guides D , which embrace and partly encircle the sides of the prop-section B of the ladder. The guides D each have their ends bent so that the ends extend toward each other, overlying the outer sides, the edges, and extending over a part of the inner sides of the side pieces of the prop-section.

The prop-section B consists of parallel side pieces, which are passed through the guides D , the rungs which connect the side pieces being of equal length, and the upper ends of the side pieces are beveled to engage at the proper angle the edges of the step-section. The side pieces of the prop-section are provided with outward-projecting pins E , which engage the upper edges of the guides and the brackets at points above the pivots which connect the guides and brackets when the prop-section is in its lowest position and parallel with the step-section. When the parts are positioned for use as a step-ladder, the pins E engage the upper edges of the guides to one side of the pivots, the tendency being to turn or rock the guides so that they will clamp the side bars of the prop-section.

When it is desired to provide an extension-ladder, the shelf is turned upward, as shown in Fig. 4, and the prop-section is then slid upward. The plates are swung to project beyond the platform, and when a rung of the prop-section engages the hooked portions of the plates the two sections of the ladder will be held securely in line with each other.

When used as an ordinary step-ladder, the plates or hooks B'' may be used to suspend a bucket or other article therefrom, and when the shelf is turned upward and the plates are turned inward the hooked end of the plates will engage the upper end of the shelf and hold the same from swinging downward.

Having thus described my invention, what I claim as new, and desire to secure by Letters Patent, is—

In an extension step-ladder, the combina-

100

tion of a step-section having a platform, plates pivoted to the platform and adapted to be swung beyond the edge thereof, brackets attached to the side pieces of the step-section, 5 guides the end portions thereof being in-turned said guides being pivoted to the brackets, a prop-section maintained in sliding engagement with the guides, the side pieces of

the prop-section having the upper ends beveled, substantially as shown and for the purpose set forth.

PHILIP HERDER, JR.
